UNITED STATES PATENT OFFICE

2,436,603

PNEUMATIC SIREN

Donald D. Ritchey, Brookmont, Md.

Application May 15, 1943, Serial No. 487,185

6 Claims. (Cl. 116—147)

1

This invention relates to a sound device and has particular relation to a device which provides interrupted sound.

It has been found that with the usual warning devices used as alarms as, for example, the sirens on emergency vehicles, there has been considerable confusion, particularly in traffic, due to the fact that a continuous uninterrupted noise will not attract the attention of persons whose minds are occupied as by the safety of the pedestrians on the street.

It has been found that since no attention is paid, by the average motorist, to the noise from the gearing of a heavy truck or bus, when the siren of an approaching emergency vehicle is heard at a distance, it does not register as a warning noise.

I have discovered that a continual interrupted noise is quickly distinguished from the noise of a gearing and that motorists react at once when such a noise is heard.

The primary object of this invention is the provision of an improved sound device having an interrupted tone to more pointedly attract the hearer's attention without increasing the volume.

Another object of the invention is the provision of an improved sound device wherein the sound is interrupted at predetermined intervals for a given set of conditions.

A further object of the invention is the provision of an improved sound device having automatically operated valve, means rapidly increasing and decreasing the area of the admission opening of a siren.

Still another object of the invention is the provision of an improved sound device having pneumatically operated valve means to control the operation of the sound device interruptedly. A still further object of the invention is the provision of an improved sound device having pneumatically operated valve means for controlling the opening of the valve means and resilient means for closing the same.

Another and still further object of the invention is the provision of an improved sound device wherein a siren is provided with a valve for controlling the passage of air therethrough and pneumatic controller means operated by the partial vacuum created within the siren.

Another and still further object of the invention is the provision of an improved sound device wherein a siren is provided with a valve controlling the passage of air therethrough with pneumatic controller means for moving the valve quickly after a given movement is made in one direction, and for returning the valve to its for-

2

mer position after the controller has moved in the opposite direction.

Another and still further object of the invention is the provision of a sound device having valve means with electrically operated means for controlling the movement of the valve.

Another and still further object of the invention is the provision of a sound device having electro-magnetic means for controlling the operation of a valve and electric means for controlling the electro-magnetic means.

Other and further objects of the invention will be apparent to those skilled in the art from a reading of the complete specification.

Referring now to the drawing wherein are illustrated various types of modifications of the invention.

Fig. 1 is a partial cross section of a modification of the invention which utilizes the partial vacuum created by the siren to operate the control valve.

Fig. 2 is a side view of the structure shown in Fig. 1 with the controller pneumatic expanded, but with parts cut away.

Fig. 3 is a view similar to Fig. 2 with the controller pneumatic collapsed.

Fig. 3a is a modified form of a device to draw air from and admit air to the controller pneumatic of Figs. 1 to 3.

Fig. 3b is another form of the structure of Figs. 1, 2 and 3. Fig. 4 is a front view of a modified form of valve and valve control as operated electrically instead of pneumatically, with the casing removed.

Fig. 5 is a view similar to Fig. 4 but illustrating the shutters in the open position.

Fig. 6 is a side view of Fig. 4 but with the cover shown sectionally.

Fig. 7 is a partial sectional elevational view 40 of a modification of the invention wherein a reversing mechanism similar to the usual windshield wiper motor is used.

Fig. 8 is a top plan view of Fig. 7.

Fig. 9 is a side view of a modified form of the invention using two cam-controlled valves.

Fig. 10 is a view of Fig. 9 from the right.

Figs. 11 and 12 are side and front views, respectively, of another modification.

Similar reference characters refer to the same or similar parts throughout the specification and drawing.

Referring particularly to Figs. 1 to 3, 20 designates the motor and 21 the siren interrupter of the siren. To the intake side of the siren stator provided with apertures in its periphery is secured a plate 22 which may extend over the

edge of the siren stator. The plate 22 is provided with lugs 23 for securing the plate in place on the siren stator.

To the side of the plate 22 is secured the stationary member 24 of the pneumatic controller 25. Hinged to the member 24 by the hinge 26 is a movable member 27 of the controller 25. On the outer side of the movable member 27 is a post 28.

A tubular member 29 is secured within an opening of the stationary member 24 and opens into the intake of the siren. Within the tubular member 29 is pivotally mounted the valve 30 having an extension extending through the wall of the tubular member 29 and of sufficient length to provide an operating end 31. To this operating end 31 is secured the bell crank arm 32 which when moved, moves the valve 30 on its pivots. Secured at one end to the crank arm 32 is the tension spring 33. The opposite end of the spring 33 is secured to the post 28 at a notch 28a. The position of the notch is preferably at a point where the spring 33 will make the same angle with the crank arm 32 whether the pneumatic controller is at the limit of movement in either extended or collapsed position. When the pneumatic controller is collapsed the spring will be on one side of the valve axis and when expanded, it will be on the other side.

With this construction, a predetermined movement of the pneumatic controller movable member 27 takes place before the valve moves. As the axis of the spring 33 is moved by the pneumatic controller past the valve axis, the spring 33 acts to move the valve quickly from one limit of movement to its opposite limit of movement. These limits of movement may be when the valve is fully open or fully closed. Suitable stops 35 and 36 are provided to stop the valve at either open or closed position.

It is to be noted that the power pneumatic is circular in outline. In order to gain the greatest area and therefore the greatest power, the movable member of the pneumatic controller surrounds the tubing 29, and has, an opening large enough to pass over and clear the tubing 29 and pivot on its hinge 26 with sufficient clearance. To seal the space between the outside of the tubing 29 and the opening in the movable part of the pneumatic controller, bellows material is secured to the edge of the opening in the movable member and also to the tubing member 29, as shown at 34. This construction permits the pneumatic controller to be practically the size of the siren stator without protruding much at the sides.

One way to exhaust the air from the pneumatic controller is by a controllable valve device 37 having a screw valve 37a which by adjustment will control the exhaust from the power controller to the tubing 29 and thence to the rotor of the siren.

By this construction, as soon as the siren is started, there is a tendency to drive the air out at the periphery of the siren stator by centrifugal force but with the valve 30 closed, the air is prevented from escaping through the siren stator. This exhaust tendency exhausts air through the valve device 37, thus collapsing the pneumatic controller. As the movable member 27 moves the spring 33 over the center, the valve is quickly opened. This destroys the vacuum in the tubing 29, permits the air to pass and sounds the siren.

However as soon as the vacuum in the tubing

29 is destroyed the air begins to enter the pneumatic controller through the valve device 37 and the return spring 38 expands the pneumatic controller, returning it to its normally expanded position. As the spring 33 again passes the valve axis, the arm 32 is moved to the other limit of movement and the valve is quickly closed. Again vacuum is built up and the cycle is repeated. The closing of the valve 30 interrupts the flow of air and its opening permits the flow to start.

In this way, the valve opens and closes alternately and starts or stops the sound of the siren, almost instantaneously. By this construction a very unique alarm is sounded—one which is not easily mistaken for other noises of machinery of automotive vehicles which may be met in the streets. By varying the point of holding the spring 33 on the post 28 and the setting of the screw valve 37a and the tension of the spring 33, the frequency of cycle may be controlled. A casting 40 is secured in place by the screws 40a and breathing holes 41 are provided to give the pneumatic controller free movement.

Fig. 3a is a fragmental sketch showing a modified form of the inlet and outlet control of air to and from the pneumatic controller 25. As illustrated, the pneumatic controller 25 has been collapsed and is about to cause the bell crank lever 32 to trip from its position as shown and move to the position illustrated in Fig. 3. This causes a push on the rod R which is pivoted to the bell crank lever 32.

The lower end of the rod R is pivoted to a swinging valve V which is pivoted on a block B at the pivot P. The free end of this valve V in one position, as illustrated in full lines, covers an opening in the block B which is connected to the conduit A to atmosphere. In dotted position, the valve V covers the opening E which is connected to the intake manifold of an internal combustion motor or any other source of vacuum.

As the valve 30 is moved by the bell crank lever 32, the latter also moves the valve V to its other extreme, thus alternately connecting the openings A and E to the interior of the pneumatic controller 25.

The opening E is opened to the interior of the pneumatic controller 25, as the latter approaches the point of greatest expansion. At the same time the atmospheric port A is closed. The air now begins to exhaust from the pneumatic controller 25 and collapse the same. As the pneumatic controller approaches the position shown in Fig. 3a, the valve V will operate from full line position to dotted position. This will connect the interior of the pneumatic controller 25 to the atmosphere by the conduit A and the spring 38 will cause the pneumatic controller 25 to expand. On reaching expanded position another cycle will begin.

In Fig. 3b the valve VV is directly connected to and is controlled by the valve 30 to open and close the port AA to atmosphere, this action corresponding to the action of the valve V and port A, already described.

Any suitable main cut off valve may be used on the exhaust connection E either in connection with or independent of the switch controlling the power to the motor 20.

In the embodiment illustrated in Figs. 4, 5 and 6, 120 designates the plate which corresponds to the plate 22 of Fig. 1 and is secured to the siren stator 121 as by suitable lugs 122.

In this form, there are a plurality of shutters 75 which operate as a valve. These shutters 123 are

pivoted in angles 124 which are secured to the plate 121 at the sides of the opening 121a. The shutters 123 are provided at one end, each with a small crank 123a. These cranks are all controlled by a single bar or link 125. The link 125 has at one end a spring 126 which is, at its other end secured to a bracket 127 mounted on the plate 120.

To the opposite end of the link 124 is connected a small spring 128 which is connected to a movable member 129 of the solenoid 130. The solenoid 130 is connected on one side, electrically, to a thermostatic control member 131 which periodically connects and disconnects the current. When the switch (not shown) is closed, the control member 131 connects and disconnects automatically, the current to the solenoid, thus operating periodically the shutters 123. As the current is cut off, the spring 126 at once operates to move the link 125 and close the shutters. If desired, the terminals of the thermostatic control and the solenoid may be connected to the switch which controls the operation of the siren motor. Or, if desired, a separate switch may be used. As these switch devices are not, per se, part of this invention, they will not be further described.

The casing 132 with its opening 132a is provided to protect the working parts from injury and may be of any suitable shape.

When the switch which controls the solenoid 130 and the thermostatic control member 131, is closed, the member 131 will operate to cause the movable member 129 to pull on the link 125 opening the shutters 123. As the control member 131 breaks the circuit, the spring 126 causes the shutters to close. This alternate opening and closing of the shutters causes the interruption of the operation of the siren to produce noise, at the same time permitting the operation of the siren to continue.

When controlled by a single switch the motor is caused to operate continuously while the signal is being sounded. With the siren stator and its coacting parts in operation, an interrupted signal is in continual operation until the circuit is broken.

Referring now particularly to Figs. 7 and 8, 220 illustrates the motor of the siren and 221 its stator.

On the intake side of the siren stator is a plate 222 to which is attached the tubing 223. Within the tubing 223 is a valve 224 which is pivoted in the wall of the tubing 223. On an extension of one pivot is mounted a bell crank arm 224a. This bell crank arm moves the valve 224 toward open and closed position to increase or decrease the amount of air permitted to enter the tubing 223, as will be presently described. Stops 225 and 226 provide limits of movement in the open and closed positions respectively.

In order to operate the crank arm 224a, I provide an exhaust-operated unit having a casing 227. Within the casing 227 is a blade which wipes through an arc in a suitable chamber 229 in the casing 227. To the pivot of the blade 228 is secured an arm 230 which moves back and forth over the bell crank 224a.

A suitable valve mechanism is provided in the valve casing 231. A shut-off valve 232 connects and disconnects the valve casing 231 with a source of exhaust as the intake of an internal combustion motor through the inlet 233.

The operation of the valve within the valve casing 231, alternately places the sides of the

chamber 229 on opposite sides of the blade 228, in connection with the atmosphere and exhaust, respectively. As the details of the reversing mechanism of the valve casing 231 are not a part of this invention, per se, further details will be omitted.

During operation, the arm 230 moves alternately from its solid line position of Fig. 8 to the dotted line position, and return, repeating this cycle until the cut off 232 is operated to close the exhaust connection.

A spring 234 of sufficient strength to move the bell crank lever 224a and the valve 224 is connected at one end to the end of the arm 230 and at its other end to the bell crank arm 224a. It is to be noted that as the arm 230 starts to move about its center, the spring 234 will be expanded. No movement of the bell crank arm 224a will take place until the axis of the spring passes through the plane containing the axis of the bell crank arm end and the axis of the pivots of the valve 224. As soon as this passing takes place, the valve 224 is quickly moved to its other extremity. This same action is reversed when the arm 230 moves in the opposite direction, the valve 224 being moved to its original position. As the arm 230 arriving at its extreme position reverses the valve in the valve casing 231, this movement of the arm 230 in reversed directions, moving the crank arm 224a and the valve 224, continues as long as the cut off valve 232 is open and the exhaust is applied.

Referring now particularly to Figs. 9 and 10, the number 320 designates the siren motor and 321 the stator.

Secured to the top of the frame of stator 321 is a bracket 322. Pivotally mounted on the bracket 322 is a cam 323 having a cam groove 324. On the edge of the inlet side face of the stator, 40 are mounted a pair of complementary wing valves 325, 326, pivoted respectively at 325a, 326a.

The cam groove 324 is elliptical in shape. Arms 325b, 326b extend from the wing valves 325, 326 and have small rollers at their respective ends, 45 in opposite sides of the cam groove 324. When the ellipse is in the horizontal position as shown in Fig. 10, the wing valve members 325, 326 are in closed position and when the elliptical cam is vertical, the wing valve members 325, 326 are in open positions.

The cam member 323 which carries the cam groove 324 is mounted on a shaft 327 having at its other end a bevel gear 328. This bevel gear 328 is in mesh with another bevel gear 329. The 55 bevel gear 329 is mounted on the shaft 330 which carries at its lower end a worm wheel 331.

The worm wheel 331 is in coactive operative engagement with a worm 332. This worm 332 is mounted on an extension of the siren shaft as 60 shown at 333 in Fig. 9.

Brackets 334, 335 are provided for support of the bearings for the shafts 327, 330.

It will be noted in the form illustrated that whenever the motor 320 is in operation the valve 65 members 325, 326 are in alternate opening and closing operation. This will continue as long as the motor 320 operates. While a single motor operates both siren and valves, this is not necessary.

In Figs. 11 and 12 is illustrated the invention 70 applied to a constantly rotating automobile fan belt shaft.

The numeral 400 designates the motor block from which extends the shaft 401. On this shaft is mounted the conventional V-pulley 402 to rotate 75 therewith. Supported on the shaft 402 but non-

rotatable therewith, is the siren stator 403, which has bearings 404a with the shaft 401 and is prevented from rotation by the jaws 403a in contact with the bar 404. This bar 404 is mounted rigidly on the block 400.

The usual rotor of the siren is mounted on the shaft 401 to rotate therewith and carries the usual fan blades 405.

Mounted on the non-rotating stator 403 is a bracket 406 which carries a solenoid 407. This solenoid 407 has a movable member or plunger 408 which is connected tangentially as at 408a to a band 409 surrounding the siren stator. This band 409 has openings corresponding to the openings of the stator and when moved one space will close, or open, all of the openings of the stator.

A suitable thermo-electric control member 410 is mounted on the opposite side of the bracket 406 and is electrically connected to the solenoid 407 to cause the latter to be energized and de-energized alternately and automatically, when the current is turned on. A spring 411 connects the band 409 with a rigid portion of the motor as the rod 404 to return the band to the point where the interruptor openings will be closed.

When current is put on through the thermo-electric device 410 the latter will operate to energize and deenergize the solenoid 407, causing the solenoid to alternately pull the band 409 to open position and then release it for closure by the spring 411.

In this form the rotor of the siren is in operation as long as the motor 400 operates, the siren sounding only when the band 409 is moved by the solenoid plunger 408.

While various modifications of the invention have been illustrated and described, it is to be understood that the disclosures are merely illustrative and that modifications and changes may be made without departing from the spirit of the invention and within its scope as claimed.

Having described my invention, what I claim is:

1. A sound device comprising a siren having an air passage, means for automatically alternately increasing and decreasing the amount of air progressing through the siren including a valve in the air passage, a circularly shaped pneumatic controller having an opening and a hinge at one side, the air passage to the siren passing through the pneumatic controller.

2. A sound device comprising a siren having an air passage, means for automatically alternately increasing and decreasing the amount of air progressing through the siren including a valve in the air passage, a circularly shaped pneumatic controller having an opening and a hinge at one side, the air passage to the siren passing through the pneumatic controller, a crank means attached to the valve and means between the crank means and the movable member of the pneumatic controller to alternately move the valve in opposite directions.

3. A sound device comprising a siren having an air passage, means for automatically alter-

nately increasing and decreasing the amount of air progressing through the siren including a valve in the air passage, a circularly shaped pneumatic controller having an opening and a hinge at one side, the air passage to the siren passing through the pneumatic controller, a crank means attached to the valve and means between the crank means and the movable member of the power pneumatic to alternately move the valve in opposite directions and means including a pneumatic connection between the siren air passage and the pneumatic controller and coacting with the valve to automatically reverse the operation of the pneumatic controller.

4. A sound device comprising a siren having an air passage, means for automatically alternately increasing and decreasing the amount of air passing through the siren comprising a valve in the siren air passage, a circularly shaped pneumatic controller having an opening, the air passage to the siren passing through the pneumatic controller, a crank means attached to the valve, resilient means having one end connected to the pneumatic controller and the other end connected to the crank and mounted to be on one side of the valve axis when the pneumatic controller is inflated and on the other when it is deflated and means including a pneumatic connection between the siren air passage and the pneumatic controller and coacting with the valve to automatically reverse the operation of the pneumatic controller.

5. A sound device comprising a siren having an air passage, means for periodically and alternately permitting and stopping the passage of air through the passage to the siren including an automatically controlled valve means, the siren and valve means being operatively connected to and operated from the same air power source.

6. A sound device comprising a siren having an air passage, means for periodically and alternately permitting and stopping the passage of air through the passage to the siren including an automatically controlled valve means, the automatically controlled valve means having an air pressure connection to and operated from the pressure in the passage.

DONALD D. RITCHHEY.
